Primary Examiner — Karen S Acker*Assistant Examiner* — Elizabeth S Ko(74) *Attorney, Agent, or Firm* — Barclay Damon LLP(57) **CLAIM**

The ornamental design for an adjustable hanger assembly for concrete, as shown and described.

DESCRIPTION

FIG. 1 is a front perspective view of an adjustable hanger assembly for concrete, according to my design;

FIG. 2 is a front facing view thereof, the rear facing view being a mirror image;

FIG. 3 is a top plan view thereof;

FIG. 4 is a bottom plan view thereof;

FIG. 5 is a left end view thereof, the right side end view being a mirror image;

FIG. 6 is a perspective view of the base member of the adjustable hanger assembly of FIGS. 1-5;

FIG. 7 is a front facing view thereof, the rear facing view being a mirror image;

FIG. 8 is a top plan view thereof;

FIG. 9 is a bottom plan view thereof;

FIG. 10 is a left end view thereof, the right end view being a mirror image;

FIG. 11 is a front perspective view of a frame member of the adjustable hanger assembly of FIGS. 1-5;

FIG. 12 is a front facing view thereof, the rear facing view being a mirror image;

FIG. 13 is a top plan view thereof;

FIG. 14 is a bottom plan view thereof;

FIG. 15 is a left end view thereof; and,

FIG. 16 is a right end view thereof.
